OF CALIFORNIA.

RADIOTELEGRAPHY.

1,306,223.

Specification of Letters Patent. Patented June 10, 1919.

Application filed May 15, 1916. Serial No. 97,437.

To all whom it may concern:

Be it known that I, LEONARD F. FULLER, a citizen of the United States, and a resident of the city and county of San Francisco, State of California, have invented a certain new and useful Improvement in Radiotelegraphy, of which the following is a specification.

The invention relates to transmission systems of radio telegraphy and particularly to a means of signaling.

An object of the invention is to provide a simple and efficient signaling system for radiotelegraphy transmission stations.

The invention possesses other advantageous features, some of which, with the foregoing, will be set forth at length in the following description where I shall outline in full that form of the invention which I have selected for illustration in the drawing accompanying and forming part of the present specification. In said drawing I have shown one specific form of my invention, but it is to be understood that I do not limit myself to the form shown.

Referring to said drawing:

The figure is a diagrammatic representation of a radiotelegraph transmission system, with one form of the apparatus of my invention arranged therein. The system includes a suitable source of oscillations, preferably continuous oscillations, such as the arc 2 which is inclosed in a hydrogen atmosphere. Current is furnished to the arc by a direct current generator 3, between which and the arc are arranged suitable choke-coils 4. One side of the arc is grounded by the conductor 5 and the other side is connected to the radiating conductor or antenna 6, through the conductor 7 and the variable inductance 8. Signaling has heretofore usually been effected by varying the wave length of the radiated wave, by short circuiting a portion of the inductance, but in high powered stations the current in the short circuit is large, making signaling difficult.

In accordance with the present invention I provide a second oscillatory circuit containing an inductance 9 and a capacity 12 and an energy consuming element which is controllable to vary the losses occurring

therein, which circuit is shunted around the source of oscillations or arc 2. When an arc is shunted by two dissimilar oscillatory circuits, it will oscillate upon one circuit or the other, but will not oscillate upon both at the same time and will oscillate upon the circuit upon which it is easiest to oscillate, to the total neglect of the other. By varying the losses in the shunt circuit, this circuit is chosen or neglected by the oscillations and consequently the radiating circuit is either neglected or chosen.

The energy consuming element comprises a core 14 formed of stiff iron laminations, which are so chosen as to provide a large hysteresis loss, especially at high frequencies. A coil 15, forming part of the shunt oscillatory circuit, is wound on a portion of the core and the current in the coil produces a flux in the core, which causes a loss of energy due to hysteresis. By reducing the hysteresis, the losses are reduced, so that the oscillations will prefer the shunt circuit to the neglect of the radiating circuit. This loss may be reduced by subjecting the iron core to a M. M. F. produced by a direct current coil 16, which is wound on a portion of the core and arranged in circuit with the battery 17. A key 18 arranged in the battery circuit provides means for opening and closing such circuit. Choke-coils 19 are preferably arranged between the battery and the coil 16 to prevent the high frequency current generated in the coil from passing into the battery, or other means to accomplish this result may be used. The size of the coil and battery are preferably such that when the key is closed, the core is saturated, thereby reducing the hysteresis and hence the losses in the shunt circuit. Due to the losses, the core becomes heated and in order to dissipate the heat, the core is immersed in an oil bath 21 through which pipes 22 carrying cooling water pass.

Signaling is accomplished by opening and closing the key 18; closing the D. C. circuit serving to reduce the hysteresis and hence the losses in the shunt circuit, thereby causing the arc to oscillate upon that circuit to the neglect of the radiating circuit and opening the D. C. circuit, causing

2
and increase in the losses in the shunt circuit and thereby causing the arc to oscillate in the radiating circuit.

I claim:

- 5 In a radiotelegraphy transmission system, a source of oscillations, a radiating circuit connected to said source, an oscillatory circuit shunted around said source, the two circuits bearing such relation to each other
10 that the oscillations will prefer one circuit to the total neglect of the other, means

in the oscillatory circuit for producing hysteresis losses and means for varying said losses to cause the oscillations to prefer the other circuit.

15

In testimony whereof, I have hereunto set my hand at San Francisco, California, this 2nd day of May, 1916.

LEONARD F. FULLER.

In presence of—
H. G. PROST.
